CLAIM

I claim the ornamental design for a single dose medicine packaging, as shown and described.

DESCRIPTION

FIG. 1 is a side view of the single dose medicine packaging.

FIG. 2 is a front view of the claimed design.

FIG. 3 is a back view of the claimed design.

FIG. 4 is a top view of the claimed design.

FIG. 5 is a bottom view of the claimed design; and,

FIG. 6 is a perspective view of the claimed design.
